US0D1083962S

(12) **United States Design Patent** (10) **Patent No.:** **US D1,083,962 S**
(45) **Date of Patent:** **** Jul. 15, 2025**

(54) **DISPLAY SCREEN OR PORTION THEREOF WITH GRAPHICAL USER INTERFACE FOR MANAGING A DIAGNOSTIC INSTRUMENT**

(71) Applicant: **Bio-Rad Laboratories, Inc.**, Hercules, CA (US)

(72) Inventors: **Gino D. Gonnelli**, Brentwood, CA (US); **Christina Marshall**, Fairfield, CA (US); **Kristin Claire Lucero**, New Braunfels, TX (US); **Aditya Vyedula Rao**, Concord, CA (US); **Theresa Forni**, Davis, CA (US); **Jeffrey Lyman Robinson**, Hercules, CA (US); **Stephen Locke**, San Rafael, CA (US); **Joan Shaughnessy Dowd**, San Ramon, CA (US); **Kimberly Johnson**, Martinez, CA (US); **John William Barry, Jr.**, Walnut Creek, CA (US); **James LeRoy Bruce, Jr.**, Crozet, VA (US); **Kristopher W. Hunt**, Milwaukee, WI (US); **John A. Trumble**, Mequon, WI (US); **Lars Kaltenbach**, Hagen (DE); **Ross Lockwood**, San Francisco, CA (US); **Gaetano Ling**, Palo Alto, CA (US); **Alessandro Argenio**, London (GB); **Pratap Ganapathy**, Menlo Park, CA (US); **Daniel Tauber**, Scotts Valley, CA (US)

(73) Assignee: **Bio-Rad Laboratories, Inc.**, Hercules, CA (US)

(**) Term: **15 Years**

(21) Appl. No.: **29/847,317**

(22) Filed: **Jul. 22, 2022**

(51) LOC (15) Cl. **14-04**

(57) **CLAIM**

The ornamental design for a display screen or portion thereof with graphical user interface for managing a diagnostic instrument as shown and described.

DESCRIPTION

The FIGURE is a front view of a display screen or portion thereof with graphical user interface for managing a diagnostic instrument, showing our new design.

The outermost broken line rectangle indicates a display screen or a portion thereof and forms no part of the claimed design.

No lightened grayscale or tonal white portions form part of the claimed design. Content contained within the box defined by the dot-dash-dot line forms no part of the claimed design.
